UNITED STATES PATENT OFFICE.

STEWART J. CORT, OF BETHLEHEM, PENNSYLVANIA; TIMOTHY BURNS, OF BUFFALO, NEW YORK; AND ROBERT S. A. DOUGHERTY AND CHARLES E. LEHR, OF BETHLEHEM, PENNSYLVANIA, ASSIGNORS TO BETHLEHEM STEEL COMPANY, OF BETHLEHEM, PENNSYLVANIA, A CORPORATION OF PENNSYLVANIA.

REGENERATIVE OPEN-HEARTH FURNACE.

Application filed December 21, 1923. Serial No. 681,939.

Our invention relates to regenerative furnaces and it has for an object to provide damper controlled throats for furnaces of the character referred to with water-cooled 5 or heat resistant liners in order to prolong the life of the throats.

A further object of our invention is to provide a damper entrance slot in the roof of a furnace of the character referred to, 10 the walls of the slot having cooling means therefor.

A further object of our invention is to provide pairs of water-cooled beams in the roof of a furnace of the character referred 15 to, the beams of each pair being spaced apart sufficiently to define a damper entrance opening and the beams of each pair being secured to opposite sides of an opposed pair of buckstays.

20 A further object of our invention is to provide pairs of spaced beams, the beams of each pair being secured to opposite sides of an opposed pair of buckstays and having secured therebetween the upper ends of 25 water-cooled liners for throats of a furnace and the space between the beams and between the upper ends of the liners serving as a damper entrance opening.

A further object of our invention is to 30 provide a furnace of the character referred to having dampers movable through openings in the furnace roof with hoods extending above the roof in order to constitute pockets to receive the dampers and to minimize the 35 leakage of gases by the dampers to the exterior of the furnace.

Apparatus made in accordance with our invention is illustrated in the accompanying drawings, forming a part of this application, in which:

Figure 1 is a fragmentary and longitudinal sectional view of a furnace embodying features of our invention;

Figure 2 is a transverse sectional view 45 taken along the line II—II of Figure 1;

Figure 3 is a fragmentary plan view of the apparatus illustrated in Figure 1;

Figure 4 is a sectional view of a damper;

Figure 5 is a transverse sectional view 50 of the damper rim;

Figure 6 is a detail view of fastening

means for securing the damper hood in place;

Figures 7 and 8 are detail views of fastening means for the damper hood cover;

Figure 9 is a horizontal sectional view taken along the line IX—IX of Figure 1;

Figures 10, 11 and 12 are detail views showing features of our improved water-cooled throat liner; and,

Figures 13 and 14 are detail and fragmentary views of our improved roof beam structure.

Referring now to the accompanying drawings for a better understanding of our invention, we show a furnace or melting chamber, at 10, which is comprised by the hearth 11, parallel side walls 12, converging end walls 13, and a roof section 14, and end chambers, at 15, comprised by bottoms 16, 70 converging side walls 17 and roof sections 18. The side walls 13 and 17 at each end of the furnace converge in opposite directions and are connected by the knuckles 19.

The end chambers 15 serve in a well-known manner as mixing or combustion chambers, gas being supplied thereto by the gas uptake 20 and air being supplied thereto by the air uptake 21.

The effective area of the throat affording 80 communication between the end chambers 15 and the furnace chamber 10 is varied or controlled by means of a transversely movable damper 23, which is movable through an opening in the roof of the furnace by a 85 cable 24 passing over a sheave 25, the cable being connected to any suitable operating mechanism well-known to those skilled in the art and constituting no part of our present invention.

The damper illustrated is of a type old in the art and it preferably comprises a central body or core of refractory material consisting of brickwork 26 surrounded by a water-cooled frame 27, the latter being supplied with a perforated tube 28 connected to a source of compressed air and serving to stir up sediment in the frame 27. The frame is connected by tubes 29 and 30 to a cross bar 31, the latter being attached to the cable 24 already referred to. The tubes 29 and 30 also serve as outlet conduits for

the rims, such tubes being connected to a common conduit 32 and the latter communicating by a hose connection 33 with a conduit 34 leading to the exhaust collector 35. 5 The tube 29 has arranged therein a smaller tube 36 which communicates with a flexible hose section 37, the latter being coupled to a conduit 38 leading to a water supply manifold 39. The other conduit 30 encloses a 10 smaller conduit 40 connected by a hose 41 to a conduit 42 leading to a suitable supply of compressed air.

The knuckles 19 at the ends of the furnace are provided with vertical liners 44 15 which are oblong box-like metallic receptacles provided with water inlets 45 connected to tubes 46 terminating near the bottoms of the box-like receptacles. The inlets 45 are connected to conduits 47 leading to 20 the supply manifold 39. Each liner is provided with an outlet 48 at its upper end and the outlets are connected to discharge conduits 49, which lead to the exhaust receiver 35.

25 The lower ends of the liners 44 are held in place in suitable recesses 50 in the floor or bottom 16 and preferably fit against shoulders 51 provided at the side walls of the throat 19. The upper ends of the liners are 30 arranged between transverse roof beams 53, to be more particularly hereinafter described. The liners are preferably provided with laterally extended vertical ribs 54 which fit corresponding vertical grooves 55 35 in the beams 53. From the structure described, it will be apparent that our improved liners 44 are readily removable from the furnace, it being only necessary to detach the conduit connections 47 and 49 and 40 lift the liners upwardly. The pairs of cooperating beams 53 define damper entrance spaces 56 for the dampers 23 and serve to support the roof sections 14 and 18 in a manner to be referred to.

45 Each of the beam sections 53 is preferably L-shaped for the major portion of the length thereof and each section is provided with water cooling conduit openings 57 communicating with the manifold 39 and 50 discharging to the exhaust receiver 35, the conduits being arranged near the surfaces of the beams which define the damper entrance opening and near the bottom sides of the beams which are exposed to the heat of 55 the furnace so as to effectively cool the beams and to oppose burning out thereof due to the heat of the furnace.

The beams 53 are opposite and complementary in design so as to provide the 60 damper entrance openings 56 and opposed vertical slots 55 to receive the tongues 54 of the liners. Outside of the liners, the beams are provided with attaching portions 58 which are adapted to be attached by bolts 65 or rivets 59 to opposed buckstays 60. The

beams 53 of a pair may furthermore be secured together by suitable bolts or keys 61.

As illustrated, the pairs of beam members 53 are arranged to extend transversely of the furnace above the throat portions thereof, such throat portions being provided by opposed reentrant or monkey walls comprised by the converging wall portions 13 and 17. The buckstays 60 are arranged exteriorly of the furnace and fit against the outside of the reentrant walls and serve to reinforce the latter. In addition to the buckstays 60, the furnace is also equipped with other buckstays 63 spaced wider apart for reinforcing the walls of the furnace. 75 80

The beam structures, comprised by the pairs of complementary beam members 53 serve to divide the furnace roof into a plurality of sections, whereby a section may be removed or repaired without disturbing other sections. Where the roof of the furnace is a unitary piece of masonry construction, it will be apparent that repairs and replacements cannot be localized to isolated sections but that the entire roof must generally be replaced. Our transverse beam structure, therefore, affords a roof construction such that the end sections 18 may be replaced or repaired without affecting the central section 14, and the latter section 95 may be removed or repaired without affecting the end sections. As illustrated, the roof section 18 is inclined slightly downwardly toward the furnace chamber 10, whereby lateral thrust is imposed upon the 100 transverse beam structure. The transverse beam structures, therefore, not only serve to isolate the roof into a plurality of sections but also serve to support or resist any lateral thrusts incident to the design of the 105 roof sections.

In order to minimize the leakage of gases through the space 56 and around the damper 23, we provide a hood at 65, which extends above the roof of the furnace and constitutes 110 a pocket or receptacle for enclosing the damper when the latter is elevated. The hood is preferably comprised by a metallic shell 66 which embraces refractory material 67, the latter defining a damper pocket or receptacle 68. The shell 66 is provided with flange means 69 at the bottom, the flange means 69 resting on the beams 53 and being preferably secured to the latter by detachable key means 70, such as illustrated in Figure 6. The key means referred to may be comprised by bolts 71 which pass through openings 72 in the beam members 53 and registering openings 73 in the flange means 69, the bolts being provided with 115 transverse slots to receive wedge keys 73. From the structure described, it will, therefore, be apparent that the hoods 65 may be readily attached and detached from the beam structures. 120 125 130

The shells 66 are preferably provided with flanges 75 near the tops upon which fit the top sections 76, the latter being notched at 77 to receive L-shaped keys 78 fitting in openings 79 in the flanges 75 and held in place by transversely extending wedges 80 as shown in Figure 8. The cover for the hood is preferably made in complementary sections in order to provide for its ready attachment 10 and removal. In removing the hood construction, the complementary parts 76 of a cover are first removed, then the damper is elevated up through the opening or pocket 68 and above the hood structure 65, whereupon the keys 70 may be removed and the hood structure taken off.

From the foregoing description, it will be apparent that we have provided a furnace having reentrant monkey walls with water-cooled or heat resisting liners in order to protect such walls at points most likely to burn out. It will also be apparent that we have provided transverse beam structures which are water-cooled, such beam structures serving to define damper entrance openings, to divide the furnace roof into a plurality of sections and to serve as tying means for opposed buckstays 60, the latter cooperating to afford lateral support for the reentrant monkey walls. In addition, it will also be seen that we provide a hood construction for the damper, whereby only openings for the conduits 29 and 30 must be provided and the leakage of gas around the damper to the outside is effectively limited.

While we have shown our invention in but one form, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

Having thus described the invention, what we claim as new and desire to secure by Letters Patent is:

1. In a regenerative furnace, in combination, inwardly extending walls defining a throat and water-cooled members disposed entirely to the inner sides of and cooperating with the innermost portions of said walls.
2. In a regenerative furnace, in combination, inwardly-projecting monkey walls and vertical water-cooled liners disposed entirely to the inner sides of the monkey walls.
3. In a regenerative furnace, in combination, inwardly-projecting monkey walls, water-cooled liners disposed entirely to the inner sides of the monkey walls, and a damper movable between the liners.
4. In a regenerative furnace, in combination, inwardly-projecting monkey walls,

buckstays cooperating exteriorly with the innermost portions of said walls, a water-cooled beam structure carried by opposed buckstays and defining a damper slot, and a damper movable through the slot and between the monkey walls. 70

5. In a regenerative furnace, in combination, end passages, dampers for the passages, pairs of opposed buckstays, and water-cooled means connected to opposed buckstays and defining entrance spaces for the dampers. 75

6. In a regenerative furnace, in combination, end passages for the furnace including monkey walls, vertical water-cooled liners 80 disposed entirely to the inner sides of the monkey walls and cooperating with the innermost portions of said walls, a damper having a water-cooled frame and movable between the liners, and an entrance slot for 85 the damper having water-cooled walls.

7. In a regenerative furnace, in combination, end passages, dampers for the passages, pairs of opposed buckstays, and water-cooled beams connected to the buckstays and defining entrance spaces for the dampers. 90

8. In a regenerative furnace, in combination, end passages, dampers for the passages, pairs of opposed buckstays, water-cooled beams connected to the buckstays and defining entrance spaces for the dampers, and hoods for the dampers carried by the beams. 95

9. In a regenerative furnace, in combination, end passages, dampers for the passages, pairs of opposed buckstays, water-cooled 100 beams connected to buckstays and defining entrance spaces for the dampers, hoods for the dampers, and means for detachably connecting the hoods to the beams.

10. In a regenerative furnace, in combination, end passages, dampers for the passages, pairs of opposed buckstays and pairs of horizontal beams constituting parts of the roof, each pair of beams being secured to a pair of opposed buckstays and defining a damper 110 entrance space. 105

11. In a regenerative furnace, in combination, reentrant side walls, a roof cooperating with the side walls, buckstays arranged exteriorly of the reentrant portions, a pair of 115 beams carried by the buckstays and defining a damper entrance space, and a damper movable through said space and between the reentrant walls.

12. In a regenerative furnace, in combination, end portions having reentrant side walls, a roof, a damper, and a transverse water-cooled beam in the roof and defining a damper entrance opening. 120

13. In a regenerative furnace, in combination, end portions having reentrant side walls and a roof, interior water-cooled liners for portions of the reentrant walls nearest to each other, a water-cooled beam structure in the roof and having a damper entrance 125 130

opening, and a damper having a water-cooled rim arranged between the liners and movable through the opening.

14. In a regenerative furnace, in combination, end portions including side walls and roofs, buckstays for reinforcing the side-walls, a pair of transverse beams secured to opposed buckstays and in the roof of each end portion, the beams of each pair being spaced apart to define a damper entrance opening, a damper for each opening, and heat resistive side wall liners opposite to the vertical edges of each damper and having their upper ends secured between the beams of a pair.

15. In a regenerative furnace, in combination, side walls, a roof, a hearth, the side walls converging and then diverging beyond the ends of the hearth, a series of pairs of buckstays cooperating with the side walls, including inset pairs cooperating with said walls near the ends at points of greatest con-

striction, water-cooled beams extending transversely and in the roof and secured to opposite sides of each of the inset buckstays, 25 water-cooled liners for the throat portion of said converging-diverging walls and having the upper ends thereof secured in place between the beams of the pairs, the space between the beams and between the liners constituting a damper entrance space, and a damper movable through said entrance space and between the liners.

In testimony whereof we hereunto affix our signatures.
